UNITED STATES PATENT OFFICE.

WILLIAM FREEDMAN, OF BROOKLYN, NEW YORK, ASSIGNOR OF ONE-THIRD TO MORRIS SOBELMAN AND ONE-THIRD TO EDWARD MORRIS, BOTH OF BALTIMORE, MARYLAND.

BLOUSE.

Application filed October 19, 1921. Serial No. 508,811.

To all whom it may concern:

Be it known that I, WILLIAM FREEDMAN, a citizen of the United States, residing in Brooklyn, in the county of Kings and State 5 of New York, have invented certain new and useful Improvements in Blouses, of which the following is a specification.

This invention relates to improvements in blouses; particularly the design of blouses 10 known as middy blouses.

An object of this invention is to provide a middy blouse which can be worn at full length and either be loose at the waist or be adjusted near its lower end to make it snug- 15 ly but comfortably encircle the wearer's body; and which further can be shortened when desired, by turning the waist band up and gathering it in, so as to make the blouse smaller and of less girth, while at the same 20 time giving it an attractive, stylish and belted appearance.

This and other objects and advantages of the invention will appear from the following description, taken with the accompanying 25 drawings, setting forth the best form of my invention now known to me; as the novel features of the invention will be defined in the appended claims. But this disclosure is, of course, illustrative only; and 30 I may make changes in what is actually shown herein, especially as to the shape, size and arrangement of parts, without departing from the scope and spirit of the invention as the same is indicated by the 35 general meanings of the terms in which the claims are expressed.

On the drawings:—

Figure 1 is a front view of a blouse according to my invention as the same appears 40 when worn at full length and loose in the waist;

Figure 2 is a front view of the same blouse made shorter by turning the waist band up and gathering it in somewhat;

Figure 3 is a bottom plan of the waist band as it appears with the parts in the positions they occupy when the blouse is adjusted as in Figure 2, and;

Figures 4 and 5 are detail views showing 50 the manner in which the waist band is made, to enable it to be shortened when desired.

The same numerals identify the same parts throughout.

In the particular description of the drawings I use the numeral 1 to indicate the body of the blouse, 2 the sleeves, 3 the collar, and 4 a pocket. At the lower end of the body 1 is the waist band 5, which is preferably made of two layers of cloth 55 stitched to the lower edge of the body 1. 60

This waist band is of sufficient length to pass entirely around the body of the blouse without constricting the girth of same, so that the blouse can be worn loose, as indicated in Figure 1, with the waist 65 band turned down and forming a border or hem. In this way the blouse can be worn with the same effect as the so called Russian blouse, with the lower part extending down toward the wearer's hips; also if desired, the waist band can be shortened to 70 make it encircle one's waist more snugly and the blouse can then be worn loose with the waist band engaging one's waist but without being turned up to shorten the 75 blouse. Such a method of wearing the blouse, simply makes the blouse loose or baggy from the waist up as will be understood. No illustration of this effect is 80 necessary.

For the purpose of enabling the waist band to be shortened, if desired, so as to make it engage the wearer's waist, either when the waist band is in ordinary turned-down position, as shown in Figure 1; or 85 turned up as in Figure 2; I provide the band with flaps 6 and 7 at opposite sides of the blouse. Flaps 6 may have holes therein and the flaps 7 may carry buttons, but obviously I may use other fastening 90 devices as well. Hence when the blouse is to be made smaller at the waist, the flaps 6 and 7 at the waist are drawn towards each other and buttoned, or otherwise secured together. This adjustment will make the 95 folds or plaits 8 in the band 5, and folds 9 in the body 1. When the blouse is to be worn at full length, like a Russian blouse, with the waist band 5 turned down, the flaps 6 and 7 are on the inside of the body 100 1 and unfastened. They are then hidden from view, but when the blouse is to be worn

without turning the band up, the flaps 6 and 7 are secured together inside of the body 1 so as to make the band 5 encircle the wearer's waist and keep the band 5 from being worn at any lower point. The blouse can then be worn as comfortably as the wearer wishes, being loose around the chest and shoulders, with an effect or appearance different from what is shown in Figure 1. 10. Further, if the wearer wishes to turn up the waist band, he can gather it in as indicated in Figure 2, which presents the waist band turned up so as to expose the flaps 6 and 7 on the outside of same. This method of wearing the blouse makes the waist band give the garment a belted or girdled effect and permits it to retain such useful articles as handkerchiefs, etc., if the wearer wishes to use it for such a purpose.

20. The flaps 6 and 7 are provided by cutting recesses in the upper and lower edges of the band 5, or the inner layer thereof when this band is made of two layers of cloth. Such recesses are indicated at 10 in Figure 4, the same being in the opposite edges of the band 5, and the narrow part of the band between each two recesses is folded together along a transverse line 11, so as to double these parts, and the sides of the recesses, which in effect, constitute shoulders 12, are stitched together; and so are the top and bottom edges of the flaps, as clearly shown in Figure 5. The buttons can then be attached and the button holes worked in or whatever other fastening devices are to be used may be secured in position.

Of course as many recesses 10 are made in the band 5 as are necessary to provide a flap 6 and a flap 7 at each side of the blouse.

40. In the above description it is apparent that with a blouse of the design specified, three different modes of wearing same can be afforded; since the blouse can be worn with the band 5 turned down and loose as in Figure 1, or with the band turned down and gathered in in order to keep the blouse from hanging down further than the wearer's waist, or with the band turned up and made of less girth as in Figures 2 and 3, 50 to give the blouse the appearance of being provided with a belt or girdle and enable the wearer to use the turned up hem or band 5 as a pocket. Of course the blouse can also be worn with the hem 5 turned up, but loose, and the flaps 6 and 7 disengaged if one wishes.

Having described my invention, what I be-

lieve to be new, and desire to secure and protect by Letters Patent of the United States is:—

60. 1. A middy blouse having a waist band provided with fastening devices on the inner side of said band, said devices when disengaged permitting said blouse to be worn loosely at full length, and being capable of engagement to lessen the girth of said band and enable the blouse to be worn with the band turned down to hold the lower end of the blouse adjacent the wearer's waist, or worn with the waistband turned up, and of lessened girth, to afford a combined pocket and girdle effect.

65. 2. A middy blouse having waist band providing a pair of flaps at each side of the blouse, each flap being made by forming a pair of recesses in the opposite edges of the band, the relatively narrow portion of the band between each pair of opposed recesses being doubled upon itself, and the opposite sides of each recess and the opposite edges of each portion being secured together, and fastening devices carried by said flaps, said device when disengaged, permitting said blouse to be worn at full length and being capable of engagement to lessen the girth of said band and enable the blouse to be worn when the band is turned down to hold the lower end of the blouse adjacent the wearer's waist, or worn with the waist band turned up and of lessened girth to form a combined pocket and girdle effect.

70. 3. A straight cut garment in the nature of a waist or blouse, the bottom portion being adapted for rolling in the form of a cuff, means for shortening the circumference of the garment near the waist line consisting of cooperating tabs attached to the inside of the garment, the tabs having fastening means near their free ends, said tabs when fastened serving to hold the cuff in rolled position.

75. 4. A middy blouse having a bottom portion adapted to be rolled to shorten the garment, means for shortening the circumference of the garment near the bottom consisting of spaced fastening members secured to the garment on the inside, said fastening means serving to hold the bottom portion of the garment in rolled position.

80. In witness whereof, I have signed my name to this specification, this 8th day of August, 1921.

WILLIAM FREEDMAN.
